UNITED STATES PATENT OFFICE.

ALBERT C. VANERKA, OF CHICAGO, ILLINOIS.

NEEDLE THREADER.

Application filed April 9, 1921. Serial No. 459,974.

To all whom it may concern:

Be it known that I, ALBERT C. VANERKA, a citizen of the United States, residing at Chicago, in the county of Cook and State 5 of Illinois, have invented a new and useful Improvement in Needle Threaders, of which the following is a specification.

An object of this invention resides in the production of a needle threader having a 10 novel sliding threading member cooperating with an improved needle and thread retaining means.

It is also an object to provide a device of this character which shall be simple and inexpensive to manufacture.

With these and other objects in view my invention consists in the novel construction, combination and relative position of the parts and members hereinafter described 20 and shown in the accompanying drawings, and particularly pointed out in the appended claims.

Referring to the drawings in which like reference characters indicate like or corresponding parts:

Figure 1 is a plan view of a needle threader embodying my invention. Figure 2 is an end elevation thereof. Figure 3 is a longitudinal section taken on line 3-3 of 30 Figure 1, and Figure 4 is a sectional plan taken on line 4-4 of Figure 2 showing the threading member in operative position.

Figure 5 is an enlarged cross section taken on line 5-5 of Figure 1, and Figure 6 is an 35 end view of the needle-supporting arm. Figures 7 and 8 are respectively enlarged side and end elevations of the end of the movable threading member.

Figure 9 is an enlarged detail of my improved threader showing the operative position of the threading bar in dotted lines. Figure 10 is an enlarged sectional view 40 taken on line 10-10 of Figure 9. Figure 11 is an enlarged cross section taken on line 45 11-11 of Figure 9, and Figure 12 is a view in perspective of the bracket 21.

Referring to the illustrations, 10 indicates a longitudinally slidable threading plate 50 provided with an extending integral operating bar 10^A and having a long integral threading member 10^B of comparatively narrow width to permit its passage through the eye of a needle 11. The threading plate 10 is slidable between the supporting body 12 and the cover plate 13 which is formed with

longitudinal bent edges 13^A adapted to embrace the supporting body 12 and thus confine the threading plate therebetween. Normally the cover plate 13 rests with the end integral flange stop 14 against the end of 60 the supporting body 12.

The needle 11 is shown resting against the narrow side retaining bar 12^A which is formed of a narrow integral right angularly disposed extension of the body 12. 65 The eye end of the needle rests against the abutment bar 12^B which is also formed of an upwardly bent narrow strip integral with the body 12. The other end of the needle is supported on the L-shaped end 15^A of 70 the supporting arm 15 which is curved as at 15^B to afford thumb clearance for the insertion and removal of the needle. One end of the bar 15 is rigidly secured to the plate 75 body 12 by rivet 16.

Additional needle retaining means are provided in a wire spring 17 which is firmly attached at one end to the screw 18 mounted in the ear 15^C which ear is formed integral with the arm 15. The upper end of the wire 80 spring 17 projects through an opening extending through the plate 12 and arm 15. It is thus evident that the needle is normally confined between the upper free end of the spring 17 and side bar 12^A. 85

The cover plate 13 and the body 12 are respectively recessed at 13^B and 12^C and it will be observed that both recesses are in alignment or register and have the left-hand side located slightly to the right of the 90 end of the threading member 10^B, when such member 10^B is in its normal back position (see Fig. 1) ready for the forward threading movement. It will also be observed that the recesses 13^B and 12^C are cut inwardly to 95 a distance slightly beyond the center line of the threading member 10^B so that when the thread is passed into the recesses the thread will be in alignment with the center line of the threading member 10^B. 100

In order to guide and facilitate the passing of the thread into the recesses 13^B and 12^C and also to retain it, I have provided a wire spring guide 20 one end of which is secured by the rivet 19 to the bottom of the body 12 and the free end 20^A being movable under the integral extension 21^A of the supporting bracket 21 which is also riveted to the body 12. The intermediate portion 20^B is bent at an angle to provide an angular 110

guide for the thread to the recesses mentioned. The upper portion of the bracket is formed with an integral ear 21^c which supports the over-hung portion of the spring 5 guide 20.

Additional thread retaining means are provided in spring pressed button retainer 22 which comprises a stationary disk member 22^A having riveted connection 22^B with 10 the cover plate 13 and a stub extension 22^C on which is loosely mounted the retaining disk 22^D. The disk 22^D is dished, as shown in Figure 5, to accommodate the leaf spring 22^E which is held to the stub 22^C by the tap 15 screw 23. It is obvious that the spring 22^E will retain the two disks 22^A and 22^D together and that the thread can be readily passed over their beveled edges between them for retainment.

20 Referring particularly to Figures 7 and 8 which show an enlarged detail of the end of the threading member 10^B, it will be noted that flat bar 10^B is small enough to pass through the needle's eye, that it is recessed 25 at the end as at 24 to provide a socket for the thread, and that longitudinal slots 25 are cut back in the sides of the bar 10^B from the recess 24. The slots 25 are preferably formed of a converging section both in 30 width and length. The provision of these slots 25 permits the passage of the thread

and bar 10^B through the eye of the needle without jamming.

I claim:

1. In a needle threader and in combination, a body, a cover plate for said body, a curved arm needle support extending from said body, needle retaining means on said body, a spring secured to said arm support and co-operating with said arm support and 35 said needle retaining means on said body for releasably retaining a needle, a comparatively long and narrow threading bar slidably mounted between said body and said cover plate, a recess in said body, a recess 40 in said cover plate, said recesses being in register and adapted to engage the thread in the direct path of the threading bar for engagement thereby, means for drawing said threading bar and thread through the eye 45 of the needle, spring means for releasably holding the thread between said recesses, and said needle retaining means on said body comprising an integral side bar and an integral abutment bar.

2. The needle threader as specified in claim 1, in combination with spring means 50 for releasably holding the thread between said recesses.

In witness whereof, I have hereunto subscribed my name.

ALBERT C. VANERKA.
